FUEL MIXING AND DELIVERY SYSTEM

James A. Harrison, Southfield Township,
Oakland County, Mich.

Application February 1, 1946, Serial No. 644,755

13 Claims. (Cl. 137—88)

1

This invention relates to a novel method of and apparatus for mixing and proportioning gases and air for producing and supplying a combustible fuel mixture and particularly to such a method and apparatus especially adapted for industrial use in gas fired appliances.

Heretofore, gas mixing and proportioning systems for gas fired furnaces have been limited to a narrow range in the selection of the number and the size of burners and in the selection of the proper size of the proportional gas-air mixer to supply the burner selected. Frequently, after such equipment had been installed it was found necessary to send back for parts of different sizes to meet the particular operating condition. Most commercial equipment of this kind has been made with interchangeable parts of different sizes for just such purposes. One commercial system, for example, provides some twenty different sizes of air jet and Venturi sleeve devices from which the purchaser is required to select the size which will operate most effectively. Another system has a removable machined Venturi insert for which different sizes may be substituted to obtain the desired firing characteristics. A third system, for example, employs an oversized air jet and Venturi sleeve having a removable rod therein for which substitutes of different sizes may be made to obtain the desired operating conditions.

In all such systems heretofore used, no valves were used between the mixing devices and the burner outlets as the presence of such a valve would upset the ratio of the air jet area to the area of the burner orifices. In the systems heretofore used the maximum turn down ratio from full capacity to minimum capacity has been approximately 4 to 1. This limited range plus the multiplicity of interchangeable parts of different sizes has made for relatively costly and inefficient gas combustion systems in the past.

An important object of this invention is to provide an improved method of and apparatus for mixing, proportioning and supplying a combustible fuel mixture to gas fired furnaces which eliminates the necessity of providing interchangeable parts of different sizes and the necessity of determining which of several interchangeable parts will obtain the maximum effectiveness. Another object of this invention is to provide such a method and system which furnishes within the limits of the equipment any mixture pressure desired by the simple expedient of adjusting one controlling device. Another object of this invention is to provide a fuel combustion system for gas fired appliances which

increases the range of the turn down ratio many times over that heretofore obtained. An important result of this invention is the ability to use a greater number of burners in the system to make up the total capacity and by means of valves or gas cocks to separately turn on or off the burners or operate them at any intermediate condition to suit an intricate heating cycle or to vary the heating operation of one part of the furnace with respect to any other part.

An important object of this invention is to provide a novel method of and apparatus for controlling the supply of combustible fuel wherein a constant pressure is maintained in the system and the orifice of the burners are varied automatically depending upon the pressure of the gas-air mixture supplied thereto. As a result, an infinite "turn-down" ratio is available and the orifice area of the burner or burners will always be just exactly equal to that necessary to pass the volume of mixture being supplied. Thus the system as a whole exhibits a constant pressure and one or more variable burner orifices automatically responsive to the pressure of the mixture in the system.

More particularly, it is an important object of this invention to provide a gas and air mixing and proportioning device having an adjustable part which eliminates the pre-selection of one of many interchangeable parts heretofore used and which when adjusted will make available any mixture pressure within the limits of the system. The novel mixing and proportioning device of this invention includes a Venturi shaped tube having a hollow member or plug therein which is adjustable longitudinally to vary the mixing pressure and through which one of the constituents of the fuel mixture is delivered. Novel control means is provided for adjusting this hollow member relative to the Venturi passage. In one form of the invention, a pressure responsive device automatically responsive to the air pressure delivered and the mixture pressure supplied is operable to adjust a movable hollow member or Venturi plug.

In another form of the invention, electrical means which may be responsive to the temperature conditions in the furnace is operable to adjust the movable member. In a third form of the invention a manual control is operable to make the adjustment.

Various other objects, advantages and meritorious features will become more fully apparent from the following specification, appended claims and accompanying drawings, wherein:

55 Figure 1 is a view of a gas and air mixing and

supply system embodying the invention partly broken away to illustrate the internal construction of certain parts thereof.

Fig. 2 is an enlarged longitudinal cross section view of the gas and air mixing device of the system illustrated in Fig. 1.

Fig. 3 is a detail view of the gas admission port of the device of Fig. 2.

Fig. 4 is a view of one end of the device of Fig. 2 modified for manual control.

Fig. 5 is a view of a modified form of control for the mixing device of Fig. 2 utilizing electrical means responsive to the temperature of the furnace for effecting control.

The embodiment of the invention illustrated in Fig. 1 comprises a plurality of burners 10 disposed in line along the outside of the furnace wall 12 and arranged to discharge burning gases through separate ports 14 associated with each burner. A manifold which may be of any suitable form supplies the combustible mixture to the burners. In the illustrated embodiment the manifold consists of a short superimposing pipe section 16 having depending sections leading to two of the intermediate burners from which branch lines 18 run to the outer burners to supply the same with fuel. The manifold section 16 connects through pipe section 20 with a gas and air proportional mixing device generally indicated at 22. The latter receives air from inlet pipe 23 leading from a blower 24 and gas from a gas main indicated at 26.

The gas main 26 is provided with a gas cock 28 for controlling the delivery of gas to the mixing device 22 and a gas pressure regulator 30 of standard construction. A temperature control valve 32 to which more detail reference will be made hereinafter is installed in the pipe section 20 between the mixer and the burner. A thermocouple 34 in a protected tube 36 is inserted in the furnace wall and is electrically connected by means described hereinafter with the valve 32 for operating the same.

Three forms of the gas and air proportional mixing devices 22 constructed in accordance with this invention are illustrated herein, and they are generally similar except for the mode of control thereover. In the system of Fig. 1 an automatically self-regulating constant outlet pressure mixing device 22 is employed. It is provided with an enlarged head 38 forming a housing for a pressure responsive diaphragm motor. The diaphragm housing communicates with the air inlet pipe 23 by means of an air delivery conduit 40 in which an air pressure regulator 42 is installed.

The air and gas mixing device is illustrated in detail in Fig. 2. It comprises generally an outer elongated stationary tubular body 44 formed of a plurality of sections threadedly or otherwise joined together in the manner shown in Fig. 2. To one end of this body 44 is the housing 38 containing the diaphragm 46 therein. The tubular body 44 has a reduced or constricted section 48 intermediate its ends which is shaped to form a pair of adjoining oppositely directed outwardly flaring wall portions. Mounted coaxially within the body 44 is an inner movable member 50 formed of several connected parts including a hollow sleeve portion 52 extending toward one end of the outer tube and a partially solid portion 54 having a conical or tapering exterior which as will be described hereinafter forms a Venturi plug cooperating with the inner wall surfaces of the outer tube 44 to form a Venturi

passage. The inner member 50 has outside dimensions less than the inside dimension of the tube 44 to thereby form an annular passage therethrough.

As shown, the plug 54 gradually tapers toward its opposite ends from a maximum diameter intermediate its ends. One tapered end portion of the plug is disposed in opposed relation to one of the outwardly flaring wall portions of the constricted section 48 and has a length substantially equal thereto. So formed and disposed, the plug cooperates with the outwardly flaring wall portions of the constricted section 48 to define a Venturi passage having an upstream converging entrance and a downstream diverging exit connected by a throat of material axial dimension. In the position of the parts shown in Fig. 2, the throat has an axial dimension approximately equal to that of the outwardly flaring wall portion of the constricted section in which the plug lies. As the plug shifts axially of the tube, as hereinafter described, it will vary the cross sectional area of the throat and thereby vary the volume of air passing through the throat.

It is noted in Fig. 2 that the conical surface of the plug 54 in the throat extends at a diverging angle to the surrounding outwardly flaring wall of the constricted section 48 with the clearance between these two surfaces gradually increasing in the direction of minimum diameter of the constricted section. This gradual increase in clearance between these two sections is in inverse relation to the decrease in diameter of the outer tube and thereby results in a throat of approximately uniform cross section throughout its length in any set position of the plug. Moreover, the inclination of these throat surfaces to the axis of the mixer will cause them to approach one another when the plug is axially shifted in one direction and to move away from one another when the plug is moved in the opposite direction thereby varying the cross sectional area of the throat and the volume of the air constituent permitted to flow therethrough.

The two portions 52 and 54 of the inner member 50 are secured together for joint operation. The hollowed sleeve portion 52 is telescopingly slidably received over a second inner sleeve 56 fixed to the end of the outer tube 44. To the opposite end of the Venturi plug 54 is fixed a coupling member 58. By means of any suitable dismountable connection a hollowed rod 60 is attached to the coupling member and forms an operating extension thereto. This connection may be in the form of a cylindrical member 62 press fitted into the end of the rod 60 and attached by means of pin 64 to the coupling member 58. The outer end of the hollow rod 60 is connected by means of opposed plates 66-66 to the diaphragm 46. The various parts of the inner member 50 are connected together for joint movement, and in response to the flexing of the diaphragm all these parts will reciprocate together relative to the outer tube 44. The telescoping connection of the sleeve portion 52 over the fixed sleeve 56 serves as one support for the inner Venturi plug member 50. An anti-friction bearing 68 through which the hollowed rod 60 slides serves as a second support for the Venturi plug member.

The air inlet into the mixer 22 is indicated at 70 and communicates with the air delivery pipe 23. The gas inlet is designated at 72 and communicates with the gas delivery conduit 26. Both inlets are on one side of the Venturi pas-

sage. The discharge outlet of the mixed gas and air is indicated at 14 on the opposite side of the Venturi passage. Air entering inlet 70 travels through the annular passage of the tube 44 including the Venturi passage and ultimately discharges from the tube through the outlet 74. Gas entering the inlet 72 is admitted through a variable slot shown in Fig. 3 into the hollowed portion 52 of the inner member and discharges therefrom into the Venturi passage through a series of annularly spaced ports 76 where it mixes with the air passing therethrough.

Referring to Fig. 3, there is mounted within the fixed sleeve 56 over which the hollowed portion 52 of the inner member telescopes a third sleeve 78 which is rotatably adjustable. Both sleeves 56 and 78 are provided with longitudinal slots which substantially register with one another to form the admission port 80 through which the gas enters the hollow interior of member 50, but by virtue of the rotatable adjustable character of sleeve 78 the port can be varied to alter the volume of gas admitted. The adjustment of the inner sleeve 78 would be made, if at all, only occasionally and depending upon the quality of the gas. At the time of installation of the equipment, tests would be run and the desired setting made at that time. In the illustrated equipment, the innermost sleeve 78 is held in adjusted position by the set screw 84 and access is gained thereto by removable cap 82. During operation of the system, movement of the Venturi plug member 50 will cause the outermost sleeve 52 to slide over the slotted port 80 and increase or decrease its area depending upon the direction of movement of the Venturi plug.

In order to prevent the escape of gas and air from the areas where they are confined before and after intermixture, any suitable form of seals may be used. As shown, a bellows type of seal 86 prevents the intermingling of gas and air at their respective inlet areas. A similar type of seal 88 prevents the escape of the fuel mixture into the diaphragm housing.

The rod 60 is hollowed as previously mentioned for the purpose of establishing communication between the gaseous fuel mixture at the discharge outlet 74 and one side of the diaphragm 46 which in this instance is the outboard side. This is accomplished by the provision of one or more bleeder holes 90 on the inner end of rod 60. The opposite end of the hollowed rod extends beyond the diaphragm and its supporting plates 66-66 and opens out into the area on the outboard side of the diaphragm. There is thus established a yielding force on one side of the diaphragm opposing the pressure of air admitted to the other side through conduit 40. As previously described, the latter is connected to the air inlet pipe 23 and the amount of air permitted to enter the diaphragm housing is varied by the pressure regulating valve 42. A control member which may be in the form of an adjustable screw 92 is provided for regulating the valve. Air admitted to the underside of the diaphragm motor is permitted to escape through the bleeder port 94. The amount of air pressure admitted to the inboard side of the diaphragm controls the movement of the Venturi plug member 50 and thereby governs the amount of mixture outlet pressure.

Functioning automatically as previously described are the burner devices 10. Each burner device has an elongated body closed at its outer end and opening at its inner end into one of

the ports 14 of the furnace wall. The body includes a nozzle portion 102 threadedly engaged in a mounting flange 104 secured to the outer surface of the furnace wall. The fuel mixture delivery pipe 18 communicates with each burner 10 and opens into its body intermediate its opposite ends. Axially reciprocal in each burner is a cone shaped plug 116 which is positioned in the nozzle and cooperates with the inner wall of the latter to vary the nozzle opening. The plug is carried on the extremity of a rod 118. The latter is yieldingly constrained by an adjustable coiled spring 120 to move the plug in the direction to close the nozzle opening. The plug is provided with an axial passage opened at both ends which serves as a duct for delivering a small quantity of gas mixture for a pilot light.

By the use of the movable orifice plug 116 and the adjustable spring 120, an infinite "turn down" ratio is available. The spring pressure would be set to equal the maximum pressure and in normal operation the pressure of the mixture admitted to the burner through the inlet pipe 18 would be sufficient to force the plug outwardly against the tension of the spring and allow the fuel mixture to flow in ignited condition into the furnace port 14. As the supply of mixture to the burner is reduced in volume the orifice plug will move inwardly and eventually if the pressure falls low enough close the burner down with the exception of the pilot light. Thus the orifice area of the burner would be just exactly equal to that necessary to pass the volume of mixture being supplied. A constant manifold pressure and an infinite turn down ratio is the result. The adjustable spring tension has the further advantage in that where a number of burners are manifolded together as illustrated herein, each burner can be set independently of the others to close at any predetermined pressure and thus provide "zone control" or zones of different temperatures in the furnace. Moreover, each burner unit may be provided with a valve immediately adjacent thereto for cutting off the delivery of fuel thereto.

The temperature control valve 32 in the line from the mixer 22 to the burner manifold is electrically controlled by a motor housed in the unit 140 attached to the pipe line 20 and by means of the leverage connection 142 is capable of swinging the valve 32 to various positions to change the volume of fuel mixture delivered to the manifold. An electrical control instrument generally indicated at 144 is electrically coupled with the valve control motor by leads 146 and with the thermo-couple 34 by leads 148, and in response to the latter closes electrical contacts in the valve motor circuit which shifts the valve 32 to various positions, which in this particular embodiment of the invention is either "high," "low" or "closed." Any other intermediate positions of the valve may be included in the control if desired.

Viewing the system of Fig. 1 as a whole, there is provided a self-balancing proportional air and gas mixing device 22 delivering a fuel mixture under a preset constant pressure to a plurality of automatic pressure responsive burners 10, each of which may be independently set to automatically close at different pressures. The inner Venturi plug member 50 of the mixing device is controlled by the air pressure operated diaphragm 46. Due to the characteristics of this novel type of mixer, if four ounces of air pressure is imposed on the inboard side of the diaphragm 46 a four

ounce burner mixture will result, regardless of the size and number of burners being supplied. If a six ounce air pressure is imposed, a six ounce burner mixture will result, and so on up to eight, nine, ten or higher ounce pressures depending upon the maximum pressures available in the combustion air. The selection of the mixture pressure is determined by the setting of the pilot pressure regulator 42 in the air line 40 leading to the inboard side of the diaphragm.

In commencing the operation of the system, if eight ounces of mixture pressure is desired and the pressure regulator 42 is adjusted to this amount, the immediate delivery of this pressure to the inboard side of the diaphragm 46 by way of tube 40 will cause the latter to move outwardly to a position approximately that shown in full lines in Fig. 2. As the pressure of the gas-air mixture builds up in the burner manifold a condition will be reached when this pressure equals that imposed on the inboard side of the diaphragm. This mixture pressure, as previously explained, is conveyed to the outer or outboard side of the diaphragm by way of the ports 90 and the hollow interior of the rod 60. If this gas-air mixture pressure should go above that imposed on the inboard side of the diaphragm, the latter will be caused to be moved inwardly because of the higher differential pressure on its outboard side. This inward movement of the diaphragm will carry the Venturi plug closer to the walls of the Venturi passage and reduce the volume of air passing therethrough and reduce the outgoing gas-air mixture delivered to the burners. Thus it is apparent that the diaphragm will automatically take a position which equalizes the pressure of the gas-air mixture with the pressure or force imposed on its inboard side. If the pressure regulator 42 is now adjusted for twelve ounce mixture pressure, the increase in pressure on the inboard side of the diaphragm will move this element and the Venturi plug to the right in Fig. 2 and permit more air to pass through the Venturi passage. The increase in gas-air mixture which will result will very quickly stabilize the diaphragm at a position where the outgoing mixture pressure equals that imposed on the inboard side of the diaphragm.

The air pressure utilized for controlling the diaphragm motor is taken for reasons of economy from the combustion air blower line 23. However, air pressure from a separate source may be used if desired. In place of the air pressure on the inboard side of the diaphragm, other force applying means may be used, such as a spring. These alternatives are suggested to show that the system is not confined to that illustrated but is capable of modification within the principles of the invention.

A particular advantage derived from this self-balancing type of system is that valve means may be installed at any point in the system beyond the mixing device, such as the temperature control valve 32, the automatic pressure responsive valves in the burners 10, and the cut-off valves 140. The latter may be adjusted while in use to completely cut off the operation of one or more burners without effecting the system as a whole in order to meet the varying heat demands of the appliance. It has been determined that the ratio of turn down with this self-balancing type of mixer is many times that heretofore obtained and one such test indicated a turn down ratio for this invention of 13 to 1. If desired, automatic

temperature control valves may be installed on each burner, or group of burners, all deriving their gaseous fuel mixture from a single self-balancing type of air and gas mixing device of the type illustrated and described herein.

The self-balancing diaphragm operated mixing device of Fig. 2 illustrates one form of the invention. Other means for shifting the inner Venturi plug member 50 may be employed and in Fig. 4 a novel manual control is shown. The air and gas mixing device is similar to that shown in Fig. 2 except for the change at the discharge end thereof where the manual control is substituted for the diaphragm motor. The outer body 45 which is generally similar to the outer member 44 of Fig. 2 has a fuel mixture discharge outlet 75 similar to 74 of Fig. 2. The inner movable Venturi plug member 51 is similar in construction to member 50 of Fig. 2 except for the connection of an externally threaded rod 61 in place of the hollow rod 60 of Fig. 2. This rod is threadedly received in a closure member 63 secured to the end of the outer body 45. It is apparent that upon rotation of the rod it will be advanced or retracted longitudinally relative to the closure member and by virtue of its connection to the inner Venturi plug member cause the latter to rotate therein and simultaneously be adjusted longitudinally within the outer member to vary the size of the Venturi passage. The end of rod 61 is squared at 65 to receive a wrench or other tool for turning, and a locknut 67 holds the rod in adjusted position. The operating end of the rod is enclosed in a removable cap 69.

In Fig. 5 an automatic electric control is shown for bodily shifting the Venturi plug member of the mixing device. The latter is similar in all respects to the device 22 of Fig. 2 except that in place of the diaphragm housing on the end of the device, a supporting plate 71 carries an electric motor housing 73 in which, as well understood by those skilled in the art, there is a reversible electric motor operatively connected to the shaft 75 for rotating it in either direction. A linkage system consisting of slotted members 77, 79 and 81 operatively connects the exposed end of rod 60 with the shaft 75. The latter includes a pin 83 on the end of the rod which is slidable along the slot of link 79 as the latter shifts and swings in response to the oscillation of the link 77.

The electric motor in the housing 73 is connected by leads 85 to a switch control generally indicated at 87. The control movements of the latter is governed by a thermo-couple 89 installed in the furnace or other gas fired appliance 91. Gas burners are schematically indicated at 93. In operation, as the temperature in the furnace varies, the control unit 87 causes the electric motor in the housing 73 to oscillate the link 77 and as is apparent from the linkage connection either advances or retracts the rod 60 and the Venturi plug to which it is attached. This will automatically vary the amount of gas-air mixture supplied to the burners 93.

What I claim is:

1. A gas and air mixing device for gas fired furnaces and the like comprising, in combination, a tube having a section thereof intermediate its ends constricted to form a Venturi passage, a hollow member co-axially arranged in said tube in spaced relation to the walls thereof extending beyond said Venturi passage on either side thereof, means mounting said member for longitudinal movement in said tube, control means

operable on one end of said member for effecting longitudinal movement thereof, means for introducing air under pressure into said tube and thereby cause the same to flow through said Venturi passage, means for introducing gas into said hollow member adjacent the end thereof opposite to that operated upon by said control means, means for discharging said gas from said member into said Venturi passage, means responsive to the longitudinal movement of said member for varying the cross sectional area of said Venturi passage, and means responsive to the longitudinal movement of said hollow member for varying the amount of gas introduced into the member.

2. A gas and air mixing device comprising, in combination, a tube having a section intermediate its ends shaped to form a Venturi passage, a hollow member mounted co-axially in said tube in spaced relation to the walls thereof and extending through said Venturi passage and beyond either side thereof to adjacent the ends of the tube, means for introducing air under pressure into said tube on one side of said Venturi passage and for discharging said air from said tube on the other side of the Venturi passage, a sleeve fixed in one end of said tube and telescopically mounted with respect to one end of said hollow member, said sleeve having an opening through the side thereof adjacent said end of the hollow member, means for introducing gas into said opening into said sleeve and thereby cause same to flow into said hollow member, means for discharging the gas thus introduced into said member into said Venturi passage for mixture with the air passing therethrough, means mounting said member for longitudinal movement in said tube, control means operable upon the end of said member opposite to that engaged by said sleeve for effecting longitudinal movement of the member, the telescoping connection of said sleeve and said member varying the gas inlet opening in the former proportionally to the longitudinal movement of the member, and means carried by said member cooperating with the walls of said Venturi passage and varying the area thereof upon longitudinal movement of the member.

3. A gas and air mixing device comprising, in combination, a tube having a Venturi passage and an inlet on one side of the Venturi passage and an outlet on the other side of the Venturi passage, a hollow member coaxially mounted in said tube in spaced relation to the walls thereof and provided with an inlet removed from said Venturi passage and one or more discharge ports opening into the Venturi passage, means for introducing air under pressure into said tube inlet to flow through the tube around said member and discharge therefrom through said tube outlet, means for introducing gas into said member inlet to flow through the member and discharge therefrom through said one or more ports into said Venturi passage where it is mixed with the air flowing therethrough, means mounting said member for longitudinal movement in said tube, means for varying the cross-sectional area of said Venturi passage proportional to said movement, pressure responsive means connected to said member for effecting movement of said member, and means counterbalancing said pressure responsive means between the pressure of the air introduced into said tube and the pressure of the air and gas mixture discharged from said outlet of the tube.

4. A gas and air mixing device comprising, in combination, a tube having a Venturi passage and an inlet on one side of the Venturi passage and an outlet on the other side of the Venturi passage, a hollow member coaxially mounted in said tube in spaced relation to the walls thereof and provided with an inlet port removed from said Venturi passage and one or more discharge ports opening into the Venturi passage, means for introducing air under pressure into said tube inlet port to flow through the tube around said member and discharge therefrom through said tube outlet, means for introducing gas into said member inlet to flow through the member and discharge therefrom through said one or more discharge ports into said Venturi passage where it is mixed with the air flowing therethrough, means mounting said member for longitudinal movement in said tube, means for varying the cross-sectional area of said Venturi passage proportional to said longitudinal movement, a diaphragm in a closed housing operatively connected to said member for effecting longitudinal movement thereof, means for exerting a yielding force against one side of said diaphragm, and means providing communication between the opposite side of said diaphragm and the tube adjacent to said outlet and rendering said diaphragm responsive to the pressure of the gas and air mixture discharged through the outlet.

5. A gas and air mixing device comprising, in combination, a tube having a section of the inner wall thereof intermediate its ends constricted to form a Venturi passage having an axially elongated frusto-conically shaped throat portion, a hollow member co-axially arranged in said tube in spaced relation to the inner wall thereof and extending through said Venturi passage and beyond either end thereof, means mounting said hollow member for longitudinal movement in the tube, a cone shaped plug carried by said hollow member intermediate its ends and positioned in said throat portion of the Venturi passage and normally in spaced relation to the wall thereof, said cone shaped plug having an axial dimension approximating that of the throat portion of the Venturi passage, said tube having an air inlet on one side of the Venturi passage and an air outlet on the other side of the Venturi passage, means for introducing air under pressure into said inlet for flow through the Venturi passage of the tube and for discharge from the tube through said outlet, said hollow member having a gas inlet remote from said Venturi passage and a gas outlet through said conical shaped plug and into substantially the downstream end of the throat portion of the Venturi passage, means for introducing gas into said gas inlet for flow through the hollow member and for discharge therefrom through said gas outlet into the Venturi passage, and control means operatively connected to the hollow member for effecting longitudinal adjustment thereof and for varying the cross sectional area of the throat portion of the Venturi passage.

6. The invention described in claim 5 characterized in that the hollow member is provided with an extension leading through one end of the tube, and that the control means constitutes a motor mounted on said end of the tube and connected to the extension for effecting longitudinal adjustment of the hollow member.

7. The invention described in claim 5 characterized in that means is provided for mounting 75 the hollow member for rotation about its axis

11

and for causing the member to move longitudinally in response to such rotation, and that the control means is operable to rotate the hollow member to effect such longitudinal movement.

8. The invention described in claim 1 characterized in that said control means constitutes a fluid motor mounted on the end of the tube and operatively connected to the hollow member to effect longitudinal movement thereof in the tube.

9. The invention described in claim 1 characterized in that said control means constitutes an electric motor mounted on the end of the tube and operatively connected to the hollow member to effect longitudinal movement thereof in the tube upon operation of the motor.

10. The invention described in claim 1 characterized in that said control means constitutes a threaded connection between the hollow member and the tube and arranged so that upon rotation of the member it will effect longitudinal movement of the member in the tube.

11. A gas and air mixing device for gas fired apparatus comprising, in combination, an outer tubular member, an inner tubular member coaxially mounted in the outer member in spaced relation to the walls thereof, said tubular members being shaped intermediate their ends to form a Venturi passage having an upstream converging entrance and a downstream diverging exit connected by a throat of material length, means for introducing fluid forming one constituent of the ultimate gas and air mixture into the outer member on the entrance side of said Venturi passage and for causing the same to flow through the space between said members and through the Venturi passage, said inner member having an axial conduit having a fluid inlet remote from said Venturi passage and a fluid outlet opening into the Venturi passage at substantially the downstream end of said throat, means for introducing another fluid forming the second constituent of the ultimate gas and air mixture into said inlet of the inner member and thereby causing the same to flow therethrough and discharge into the downstream end of the throat of the Venturi passage, means providing axial movement of one member relative to the other member, said axial movement varying the cross sectional area of the throat, and valve means associated with the fluid inlet of the inner member and responsive to the movement of said movable member for varying the amount of fluid entering the inlet.

12. In a gas and air mixing device for gas fired apparatus, a tube having the interior thereof intermediate its ends constricted to form adjoining communicating oppositely directed outwardly flaring wall portions, means for introducing one constituent of an ultimate gas and air mixture into the tube for flow through the constricted area thereof, a member coaxially disposed in said tube in spaced relation to the walls thereof, a conical-shaped plug carried on said member in opposed spaced relation to one of said outwardly flaring wall portions and cooperating

12

therewith and with the other outwardly flaring wall portion to form a Venturi passage having a converging upstream entrance and a diverging downstream exit connected by a throat of material length, said member being interiorly shaped to provide a longitudinal conduit having an outlet opening into substantially the downstream end of said throat, means for introducing the other constituent of the ultimate gas and air mixture into said conduit for flow therethrough and for discharge from said outlet into the downstream end of the throat where it mixes with the first mentioned constituent to form the gas and air mixture, means mounting the member for axial shiftable movement, and control means for shifting the member, said plug moving in response to the axial shiftable movement of the member to vary the cross section area of the throat of said Venturi passage.

13. A gas and air mixing device for gas fired apparatus comprising, in combination, a tube having a section of its length constricted interiorly to form a communicating pair of oppositely directed outwardly flaring wall portions, a hollow member coaxially arranged in said tube in spaced relation to the walls thereof and extending through said constricted section and having its opposite ends projecting beyond the outwardly flaring wall portions thereof, means for introducing air under pressure into said tube at a point removed from said constricted section and for causing the air to flow through the tube and through the annular space between the flaring wall portions of the tube and the outer surfaces of the member, a cone shaped element carried by the member and disposed opposite one of said flaring wall portions with the slope of the element and the flaring wall inclining generally in the same direction, said cone element together with the flaring wall portions forming a Venturi passage having an upstream converging entrance and a downstream diverging exit connected together by a communicating throat of material length, means for introducing gas into one projecting end of said hollow member, means for discharging the gas thus introduced from the cone shaped element into the downstream end of said throat of the Venturi passage, means mounting said member for longitudinal movement in said tube, and control means operatively engaging a projecting end of said member for adjusting the position of the member in the tube, said cone shaped element being responsive to such longitudinal movement of the member to vary the cross sectional area of said throat.
